UNITED STATES PATENT OFFICE.

GEORGE F. HOPKINS, OF JACKSON, MICHIGAN; WILLIAM K. SAGENDORPH EXECUTOR
OF SAID GEORGE F. HOPKINS, DECEASED.

CHUCK.

Application filed February 28, 1925. Serial No. 12,331.

This invention relates to improvements in chucks. It relates particularly to a lathe chuck adapted for pneumatic control although its features are available in other relations, as for hand manipulation.

The objects of the invention are,

First, to provide an improved general arrangement of parts.

Second, to provide improved actuating means for the jaws of such chuck.

Third, to provide improved jaw means.

Fourth, to provide improved adjusting means for the jaws.

Fifth, to provide improved support and ways for the jaws and means for taking up the wear.

Sixth, to provide improved lubrication means.

Objects relating to details and economies 20 of construction and operation will appear from the detailed description to follow.

I accomplish the objects of the invention by the devices and means described in the following specification. The invention is defined and pointed out in the claims.

A structure embodying a preferred form of my invention is illustrated in the accompanying drawing, forming a part of this specification, in which:

Fig. I is a detail perspective view of my improved chuck on a lathe spindle provided with pneumatic control, the parts of the lathe being indicated by dotted lines.

Fig. II is an enlarged detail face elevation 35 view of the chuck, taken from the right hand of Fig. I, a portion of the face plate being broken away to show details of construction.

Fig. III is an enlarged detail vertical sectional elevation taken on line 3—3 of Figs. II, IV, V and VII.

Fig. IV is a still further enlarged detail 40 of the jaw structure and support, taken on the irregular section line 4—4 of Figs. II, III and V.

Fig. V is an enlarged detail sectional view 45 taken on line 5—5 of Figs. III and IV showing details of the jaw adjusting screw means.

Fig. VI is an enlarged detail face view of 50 the divided jaw support for carrying the adjusting screw.

Fig. VII is an enlarged detail transverse sectional view taken on line 7—7 of Figs. III and VIII showing details of connection of the bell crank to the draw sleeve.

Fig. VIII is an enlarged detail perspec-

tive view of the draw sleeve and one of the bell cranks in detached relation.

Fig. IX is an enlarged detail sectional view through the master jaw 8, taken on section 9—9 of Figs. III and IV, showing details of the oil passage and oiling system in that relation.

In the drawing the sectional views are taken looking in the direction of the little arrows at the ends of the section lines and similar numerals of reference refer to similar parts throughout the several views.

The numbered parts of the drawing will be considered by their numbers. 1 is the live spindle of a lathe carrying a pneumatic control means, not detailed or numbered here, as the invention does not relate to it specifically. 2 is the chuck body connected to the lathe spindle by the adapter 3 in the usual way. 4 is the spider retained and supported within the chuck body and embraced by the face plate 5, through which are disposed screw bolts 6 extending through the face plate and spider and chuck body into the adapter. Additional bolts 7 extend through the face plate and chuck body for greater security and incidentally to serve to retain the bell crank pivots against longitudinal displacement.

The master jaw 8 is provided with a connecting lug 9 projecting within the spider for assisting in guiding said jaw and providing a connecting lug for the actuating bell cranks within. Bell cranks 10 are disposed within the spider and are carried by cross pivots 11 which are retained in position against longitudinal displacement by each being disposed between a pair of the securing bolts 7 which are arranged in pairs for that purpose (see Fig. II).

A short arm 101 of each bell crank engages and actuates a master jaw. The end of the arm is square and engages a cylindrical bearing member 102 disposed in transverse bearing 91 in the said lug 9 of each jaw 8. These cylindrical bearings are each provided with a longitudinal rectangular slot 103 to cooperate with the square end of the bell crank arm. A cross pin 104 in the end of arm 101 engages in cross slot 105 in the bearing member 102 to prevent lateral displacement of the bearing member.

The long arm member 106 of each bell crank extends radially inward and is connected to the draw sleeve 12 by a similar con-

nnection. The central axially reciprocating draw sleeve 12 is provided with transverse bearing seats 121 which receive the cylindrical bearing members 107 which are each 5 longitudinally slotted at 108 to receive the square end of the long arm 106 of each bell crank, so that when the draw sleeve is reciprocated it actuates the bell crank. Each bearing member 107 has cross slot 107' and 10 is engaged by cross pin 109 through the squared end of the lever arm 106, and is thus released in operative position. See Figs. II, III and VII. There may be two or more bell cranks, opening and closing the chuck 15 jaws simultaneously and accurately centering the same. Three are shown.

The draw sleeve 12 is connected to connecting rod 13 adjustably. The connecting rod 13 contains a central screw-threaded bore at 20 its end and is connected by hollow headed adjusting screw 14 to the said draw sleeve 12. A central screw-threaded nut 15 is at the inner end of the draw sleeve 12 and is journaled on the shank of the screw 14. It is retained effectively in place by a pair of lock nuts 142 which are adjusted on the said screw 14, the threaded end 141 of which extends into the screw-threaded end of the connecting rod 13. The hollow head of the screw 14 receives a socket wrench (see Figs. III and VII), and it is possible to adjust the connection of the draw sleeve to the connecting rod very accurately to secure the proper adjustment for actuation of the jaws in this way.

35 The face plate is provided with the master pilot bushing 16 which is secured to the face plate and spider by countersunk hollow headed screws 161 (see Figs. II and III). A detachable cover 17 is placed on this bushing 40 and is detachably held in place by screws 171, so that when it is desired to use the pilot bushing the cover may be removed. For ordinary work the cover is left in place to exclude dust.

45 The adjustable detachable jaws 18 are each carried by the support 20 20' and are adjustable by the screw 19. The support 20 20' is in two parts. This support is retained in place upon the master jaw by a pair of screws 50 201 and each part has laterally projecting transverse ribs 202 engaging in a suitable transverse seat 88 on the master jaw 8, which retains these parts in position. Each part 20-20' is longitudinally grooved at 203 to engage rib 89 on the master jaw—see Figs. IV and VI. These parts are recessed to receive the adjusting screw 19 which is provided with journals 191 in part 20' and journals 192 in part 20, and disposed in recess 60 193 in the said support 20 20'. Because these parts are made separable, it facilitates assembling, the screw and journals being made integral. The adjusting screw is controlled by a wrench engaging the square projecting end 194.

The adjustable jaw 18 slidably engages this support, a suitable way 181 being provided at one side with threads for engaging the screw 19. A gib 182 is clamped to the opposite side by screw studs 183 provided with screw nuts 184 for clamping and locking the jaw in place upon the support 20, 20' after adjustment by the screw 19 (see particularly Fig. IV). From this it will be seen that by manipulation of the adjusting screw 19 the jaws can be each definitely adjusted and set to any position desired, and can then be clamped securely, as indicated.

The master jaws 8 (see Fig. IV) are provided with laterally projecting slide ribs 82 with beveled outer sides 83 engaging in and extending into suitable ways between the face plate and the spider. These are provided with flat inner surfaces and beveled outer surfaces. Beveled gibs 84 with beveled faces 85 co-operate with the same and are secured adjustably in position by hollow headed pointed screws 86 through the face plate engaging corresponding notches in the gibs 84, which enables the taking up of wear at this point and insuring a very close fit between the parts, permitting of very accurate adjustment and secure clamping of the parts.

55 In the master jaw 8 I provide for lubrication of the various parts, utilizing centrifugal action for properly forcing the lubricant to the different bearings. The radial oil hole 21 (see Fig. IX) is provided with a spring cover 211 at its outer end to prevent discharge of the oil due to the centrifugal action. This is made deep into the jaw 8 to form a reservoir for the oil to be delivered outwardly and centrifugally by the rotation of the chuck.

The cross bore 212 for delivering oil laterally is closed by the screw plug 213. Oil holes 214 and 215 provide oil for the slide ways. An oil hole 216 delivers oil to the bearing 91 for the short arm of the bell crank. From this it will be seen that when the oil is introduced into the passage and the chuck is under rotation, the oil will be forced out centrifugally to these points requiring lubrication. Oil will ooze out from the bearing 91 and by capillary attraction work down over the bell crank lever and lubricate the inner end of the same. In the first place the whole structure is lubricated before the chuck is put into position. After a chuck has been put into use, oil will be effectively supplied in this way above described.

65 The master jaw 8 is provided with a projecting flange 87 which extends laterally over the face plate 5 of the chuck (see particularly Fig. IV) and serves as a cover for the opening. The inner portion of the flange extends over the outer surface of the master pilot bushing 16 (see Fig. III) and makes a complete cover for the opening during the radial movement of the jaws actuated by the reciprocating movement of the draw sleeve.

I have described and shown in detail the adjustable jaws for the chuck. Universal jaws can be made use of and can be secured to the master jaws by the screws 201. When such 5 jaws are made use of, the matter of adjustment and the like are not provided for. As these jaws are the usual jaws without any adjustment, I have not deemed it necessary to illustrate the same. Certain details 10 described and illustrated in this application are also described and claimed in my copending application Serial No. 82,685 filed January 21, 1926, which is a division of this application.

15 Having thus described my invention, what I claim as new and desire to secure by Letters Patent is:

1. In a lathe chuck, the combination of a recessed chuck body, a spider disposed within 20 said chuck body and having radial ways and a central axial bore, a face plate with radial ways corresponding to the ways in said spider, attaching devices for said body, spider and face plate, master jaws having slide ribs disposed in said ways and projecting lugs on the 25 back having transverse bearings, a draw sleeve disposed within the bore of the spider and provided with transverse bearings, actuating bell cranks disposed in the radial ways within 30 the spider and pivoted upon suitable cross-pins retained between the same by the said attaching devices, and bearing members on the arms of the bell cranks disposed in the bearings in the said lugs and in the transverse 35 bearings in the draw sleeve, coacting as described for the purpose specified.

2. In a lathe chuck the combination of a suitable chuck body, a spider within the chuck body with radial ways therein forming slide- 40 ways for master jaws, a face plate therefor with suitable radial openings corresponding to and supplementing the ways in said spider, said face plate adjacent the ways being recessed to form auxiliary ways between the

face plate and spider, a master jaw disposed 45 in each of said radial ways adapted to fit the radial ways of said face plate, each said master jaw having projecting guide ribs extending into the auxiliary ways, beveled gibs within said auxiliary ways, and pointed set screws 50 disposed in the face plate extending into the front of the face plate and abutting said beveled gibs, coacting as specified.

3. In a lathe chuck, the combination of a 55 chuck body with radial ways formed therein for master jaws, master jaws in said ways with rearward projections and provided with transverse open-side journal bearings, a draw sleeve disposed within the said chuck provided with transverse open-side journal bearings, 60 actuating bell crank levers fulcrumed in the chuck head with square-end projecting arms, and journal pin bearings with longitudinal rectangular slots slidably fitting the 65 said bell crank lever arm ends, as specified.

4. In a lathe chuck, the combination of a 70 chuck body with a way for a chuck jaw, a master jaw in said way provided with a transverse open-side journal bearing, a lever for actuating said jaw with a squared-end bearing portion, and a journal pin with longitudinal bearing slot disposed in said open-side journal bearing and embracing the squared bearing end of said lever, as specified.

5. In a lathe chuck, the combination of a 75 chuck body with a way for a chuck jaw, a master jaw in said way provided with a transverse open-side journal bearing, a lever for actuating said jaw with a squared-end bearing portion and having a cross pin therethrough, 80 and a journal pin with longitudinal bearing slot and having a central cross slot disposed in said open-side journal bearing and embracing the squared bearing end of said lever, as specified.

In witness whereof, I have hereunto set my hand.

GEORGE F. HOPKINS.
